 Patent expires February 9, 1962

15 Claims. (Cl. 315—39)

1

This invention relates, generally, to oscillation generators and it has particular relation to devices for generating ultra high frequency electro-magnetic waves.

The object of the present invention is to avoid certain disadvantages of the prior ultra high frequency generators whilst at the same time making use of the advantages which are offered by combining the means for the self-excitation of the oscillations at maximum efficiency with a hollow resonator which alone determines the oscillation frequency. The invention thus concerns a magnetron for producing ultra-short electro-magnetic waves and which is characterised by the provision for the oscillation system of a practically closed annular hollow body bounded in a radial direction by two cylindrical casings, the cylindrical casing nearer to the axis being divided into two parts by a zigzag slot which is closed in the tangential direction, said parts being at different alternating potential but at the same direct potential relative to the cathode located in the axis of the system.

An important fact as regards the present invention is that in a hollow resonator an electrical oscillation is excited by which in a known manner a continuous conversion of capacity energy into inductive energy occurs. There is a so-called magnetic dipolar excitation of the cavity whereby the latter is able to deliver energy in the form of electro-magnetic oscillations.

A number of constructional examples of the invention are illustrated in the accompanying drawings in which:

Fig. 1 is a perspective view of a hollow resonator element embodying the invention.

Fig. 2 is a schematic axial section through the electrode assembly of a magnetron embodying the invention.

Fig. 3 is a schematic axial section through another form of electrode assembly.

Fig. 4 is an axial section through an all-metal magnetron tube construction in which the resonator element constitutes the vacuum vessel or tube.

Fig. 5 is an axial section, similar to that of Fig. 4, and showing a permanent magnet and variable means therefor, and

Fig. 6 is a perspective view of a resonator chamber within an evacuated glass envelope.

The resonator element as shown in Fig. 1 is intended for use in a magnetron for generating ultra-short electro-magnetic waves. The zigzag-shaped slot Z produces in the inner cylinder the interpenetrating segments S₁ and S₂. These seg-

ments are laminations together with the outer cylinder and the radial side walls form the hollow body H which acts as a hollow resonator, the segments mutually representing the capacity and the remaining part of the hollow body the inductance of the latter. When the hollow resonator oscillates the laminations S₁ are positive and the segments S₂ negative at a certain instant. As a result of the oscillating process these charges now change places so that after a half cycle the segments S₁ become negative and the laminations S₂ positive. For this change-over the hollow body H, which acts as an inductance, is used as the inductive connection.

The more complete illustration of the electrode assembly of Fig. 2 differs from Fig. 1 in so far as a cathode K surrounded by a grid G is also shown; also that an output loop L for extracting the high-frequency energy is provided and finally perpendicularly to the axis of the magnetron metal plates P₁ and P₂ are arranged for preventing the radiation of high frequency energy. The capacity of the oscillation circuit is again formed by the adjoining segments S₁, S₂ whilst the inductance is formed by that part of the hollow body H comprising the end surfaces and the outer cylinder. The pole pieces E of a generally C-shaped magnet are positioned close to the side walls of the resonator chamber H, the pole pieces preferably having openings therethrough for the leads to the cathode K and grid G. Field windings W on the pole pieces E are energized from a direct current source, not shown, to establish a unidirectional magnetic field within the resonator chamber.

The frequency of the generated oscillations depends upon the volume of the resonator chamber and arrangements for varying the volume will be described later. A Lecher line for extracting energy from the resonator chamber also has an influence upon the frequency of the resonator oscillations, and it is thus possible to effect a frequency modulation by connecting a Lecher line L₂ across a pair of electrodes S₁, S₂, the Lecher line being closed by a variable capacity J.

Fig. 3 illustrates a further embodiment of the invention developed from the construction illustrated in Fig. 2. The cathode K is smaller and located in the immediate vicinity of the side plate P₂. The side plate P₁ can be used as a control grid if it is insulated from the remaining parts of the device. This construction is particularly suitable for avoiding the reheating effect of the cathode. A Lecher wire L₁ that is closed by a sliding bar K may be connected to an adjacent pair of the inner wall segments S₁, S₂ for extract-

ing energy from the resonator. The volume of the chamber H may be varied for adjustment of the resonator frequency by a flexible wall section W_1 and pressure screw S_3 .

If with the arrangement shown in Fig. 2 or 3 the side plates P_1 and P_2 are connected galvanically and soldered to the remaining part of the device as indicated by the weld metal W in Fig. 3; an all-metal construction can be obtained.

The embodiment shown in Fig. 4, with the exception of the insulating bushings V , is a construction of this kind. The same reference letters are used for the same elements as in the previous figures. The generator is cooled by liquid circulated through pipes R which are positioned adjacent or secured to the side walls of the chamber H in line with the ends of the segments S_1 , S_2 . The volume of the chamber may be varied by an adjustable piston M . Side walls are used here instead of side plates for protection against radiation. The plates P_4 located parallel to the side walls inside the cathode space serve as a screen inside the inner cylinder for the electrical field which occurs due to the anode potential at the said walls, thus preventing any undesirable deviation of the electrons.

The construction according to the invention possesses several advantages. It has complete electrical symmetry as regards each segment pair since all segments are of the same dimensions and are uniformly spaced circumferentially. Due to heat being conducted to the side walls the thermal loading of the anode is reduced. The all-metal construction illustrated in Fig. 4 is suitable for large powers because by constructing the resonator as a vacuum vessel it is possible to obtain a ready removal of heat from the anode. The wave length of the oscillation is determined by the mutual capacitance of the segments and the diameter of the hollow resonator. For the same wave lengths the dimensions of the generator according to the invention are larger than those of the known kinds of magnetrons. Particularly the actual external diameter of the anode is three to four times larger and this enables a better arrangement of the cathodes and control grids, even for small wave lengths. The larger radial dimension enables a spiral cathode to be used for high currents. Furthermore the axial dimension or length of the cavity resonator is less than the diameter and can be reduced to a minimum so that the pole shoes of the magnet need not be so far apart and therefore permanent magnets can be used. Since the wave length is determined by the mutual capacitance of the segments and the diameter of the hollow resonator this value is definitely fixed for a particular case. This is a considerable advantage when compared with a known construction where the wave length is not clearly defined.

As shown in Fig. 5, the side walls and the cylindrical walls of the resonator chamber H may be made of different materials, for example the inner slotted cylindrical surface S_1 , S_2 can be made of special heat-resisting material, for instance tantalum, because this is subjected to a strong heating action due to the impact of the electrons. The permanent magnet M' is made in two sections that may be separated for the introduction of the resonator chamber H between the pole pieces. The strength of the magnetic field may be varied by a magnetic shunt or by a screw 1 that adjusts a magnetic plug 2 into and out of a slot in the magnet to vary the reluctance of the magnetic

path. The cathode K may be of the large surface type, as illustrated.

As shown in Fig. 6, a resonator chamber may be mounted within a glass envelope G_1 by means of metal vanes F that are soldered or welded to the chamber and the lead-in wires. The inner wall segments S_1 , S_2 are separate strips or rods that are welded to the side walls of the chamber H .

The shape of the hollow body H can differ from that shown in Fig. 1 by bevelling the sharp edges or providing the side surfaces with recesses. The interpenetrating segments formed as a result of the zigzag slot can be made so narrow and thick that they finally become rods. The segments can be either soldered to the side walls of the hollow resonator, fitted into the resonator, as shown in Figs. 5 and 6, or fixed in any other suitable manner.

The cathode K is heated either directly or indirectly. Generally there is sufficient space to enable a large surface cathode to be used, see Fig. 5.

The all-metal construction is the most favourable as regards cooling, because it provides a maximum of metal surface. Generally both liquid and air cooling are employed, particular care being taken that the inner cylinder can readily get rid of its heat by means of a good and rapid conduction away from the side wall where the segments end.

In order to obtain full use of the magnet it is advisable to provide holes in its pole shoes M_2 into which the insulators V (Fig. 5) lying in the axis of the magnetron can be fitted exactly and through which also the leads to the cathode can pass. By this means the poles are as near to each other as possible and the magnetic field therefore attains its maximum value. In order to insert the magnetron between the poles these must be moved apart and then pushed together again. This can for instance be achieved by making the magnet in two parts which can be fitted together.

By varying the volume of the magnetron at the places where the electric or magnetic field exists it is possible to obtain a variation in the frequency of the generator oscillations; that is to say by this means it is possible to modulate its frequency. Therefore for instance by means of the described elastic deformation of the walls at the points where there is maximum electrical or magnetic energy, it is possible to obtain a frequency modulation. In the constructional example shown in Fig. 4 the strongest electrical field is in the vicinity of the axis whilst the maximum value of the magnetic field is in the neighborhood of the outer cylindrical envelope. The volume can also be varied by introducing a metal rod or piston into the inside of the resonator.

The maximum power setting of the magnetron must be adjusted by varying the magnetic field and by a corresponding voltage variation. If a permanent magnet is used it is possible to adjust the strength of the magnetic field by a variable interruption of the magnetic flux. One way of varying the field strength in the magnetron is by suitably displacing a ferromagnetic body 2 , Fig. 5, so that a variable number of lines of force are short-circuited.

I claim:

1. A magnetron comprising a cavity resonator having a cathode in the interior thereof positioned at right angles to two parallel surfaces defining the shortest dimension of said resonator, an anode structure surrounding said cathode and composed of a multiplicity of equal length anode

segments greater than two located between said surfaces and mounted with alternate segments on the same surface and adjacent segments on opposite ones of said two surfaces of said cavity resonator, and means adjacent said resonator for producing a magnetic field having flux lines extending in a direction substantially parallel to said cathode.

2. A magnetron comprising a cylindrical cavity resonator whose length is short relative to its diameter, a cathode within said resonator, and an anode structure surrounding said cathode, said anode structure being composed of an even number of equal length anode segments greater than two located between those surfaces of said resonator which define the boundaries of said length and mounted in the interior with alternate segments on opposite faces of said cavity resonator, and means adjacent said resonator for producing a magnetic field.

3. A magnetron comprising a cylindrical cavity resonator whose length is short relative to its diameter, a cathode in the center and positioned along the length of said cavity resonator, and an anode structure surrounding said cathode and which is composed of a plurality of identically dimensioned anode segments greater than two mounted in the interior, alternate segments being mounted on opposite faces of said cavity resonator, and means adjacent said resonator for producing a magnetic field having flux lines extending in a direction substantially parallel to said cathode.

4. A magnetron comprising a cavity resonator whose length is short relative to its transverse dimensions, a cathode in the interior and positioned along the length of said cavity resonator and located between opposite faces thereof, and an anode structure surrounding said cathode and composed of an even numbered multiplicity of equal dimensioned anode segments greater than two, alternate segments being directly connected to the same face and adjacent segments being connected to opposite faces of the resonator, and magnetic pole pieces at opposite ends of said cathode for producing a magnetic field.

5. An electron discharge device comprising an evacuated cavity resonator having a short dimension and a long dimension, a cathode in its interior and an anode structure coaxial with said cathode, said resonator having two substantially parallel surfaces defining said short dimension, said cathode and anode being positioned between said two surfaces, said anode comprising a multiplicity of identically dimensioned anode segments greater than two mounted with alternate segments on the same side and adjacent segments on opposite sides of said cavity resonator.

6. A magnetron comprising a cavity resonator having two substantially parallel flat surfaces, a cathode in the interior of said resonator at right angles to said flat surfaces, and an anode structure surrounding said cathode and coaxial therewith, said anode structure having a multiplicity of identically dimensioned anode segments greater than two mounted with alternate segments on the same surface and adjacent segments on different ones of said two flat surfaces, said cathode including a hollow electron emitting element having a heater therein, and shields at the ends of said cathode for confining the electrons emitted by said cathode.

7. A magnetron comprising a cavity resonator having a pair of flat surfaces defining its shortest dimension, a cathode and an anode structure in

the interior of said resonator and located between said flat surfaces, said anode structure being composed of a plurality of equal dimensioned anode segments greater than two, alternate segments being directly connected to the same surface and adjacent segments being directly connected to the opposite surfaces of the resonator, and means located externally of said resonator for producing a magnetic field with flux lines parallel to said cathode.

8. An electron discharge device comprising a cavity resonator having a pair of flat surfaces defining its shortest dimension, a cathode and an anode in the interior of said resonator and located between said flat surfaces, said anode structure being composed of a plurality of equal dimensioned anode segments greater than two, alternate segments being directly connected to the same surface and adjacent segments being directly connected to opposite surfaces of the resonator.

9. An anode assembly for a magnetron comprising a cavity resonator having annular conductive end walls and bounded in a radial direction by cylindrical conductive walls, the inner cylindrical wall being divided into a plurality of pairs of anode segments by a zig-zag slot, whereby adjacent anode segments are connected to and supported by opposite annular end walls, the axial length of said cavity resonator being short relative to the diameter of the outer cylindrical wall and the natural resonant frequency of the cavity resonator being determined by the capacitance between said anode segments and its relation to the inductance provided by said outer cylindrical wall and the annular end walls connecting the same to said anode segments, cathode means of more than filamentary diameter located within the cylindrical space defined by said anode segments and with the axis thereof parallel to said anode segments, insulating bushings closing the axial openings in said end walls and supporting said cathode means, and pipes adjacent the ends of said anode segments for the circulation of a cooling medium therethrough to cool said anode segments.

10. An anode assembly for a magnetron comprising a cavity resonator having annular conductive end walls and bounded in a radial direction by cylindrical conductive walls, the inner cylindrical wall being divided into a plurality of pairs of anode segments by a zig-zag slot, whereby adjacent anode segments are connected to and supported by opposite annular end walls, the axial length of said cavity resonator being short relative to the diameter of the outer cylindrical wall and the natural resonant frequency of the cavity resonator being determined by the capacitance between said anode segments and its relation to the inductance provided by said outer cylindrical wall and the annular end walls connecting the same to said anode segments, cathode means of more than filamentary diameter located within the cylindrical space defined by said anode segments and with the axis thereof parallel to said anode segments, insulating bushings closing the axial openings in said end walls, an insulated bushing supported by the outer cylindrical wall, and output means within the annular interior of said cavity resonator and having a lead extending through said last mentioned insulator bushing.

11. An electrode assembly as recited in claim 10, wherein the outer walls of said cavity resonator and said insulating bushings form the evacuated envelope of the magnetron.

12. A magnetron for generating ultra-short electro-magnetic waves comprising an annular hollow conductive body constituting a cavity resonator with annular end walls and bounded in a radial direction by two cylindrical walls, the inner cylindrical wall being divided into two parts by a zig-zag slot providing a plurality of pairs of interfitting anode segments supported in alternation on said end walls, the geometry of said cavity resonator being such that the natural resonant frequency is determined by the mutual capacitance of the interleaved anode segments and its relation to the inductance provided by said outer cylindrical wall and the end walls connecting the same to said anode segments, said annular end walls extending inwardly from said inner cylindrical wall to constitute parts of a sealed envelope for said magnetron, a magnet located outside of and adjacent said cavity resonator and having spaced pole pieces at opposite ends of the space defined by said inner cylindrical wall to establish a unidirectional magnetic field within said space and parallel to the axis thereof, and a cathode extending through said space parallel to the magnetic field, said pole pieces having openings therethrough in which leads to the cathode are arranged.

13. A magnetron for generating ultra-short electro-magnetic waves comprising an annular hollow conductive body constituting a cavity resonator with annular end walls and bounded in a radial direction by two cylindrical walls, the inner cylindrical wall being divided into two parts by a zig-zag slot providing a plurality of pairs of interfitting anode segments supported in alternation on said end walls, the geometry of said cavity resonator being such that the natural resonant frequency is determined by the mutual capacitance of the interleaved anode segments and its relation to the inductance provided by said outer cylindrical wall and the end walls connecting the same to said anode segments, means positioned outside of and adjacent said cavity resonator to establish a unidirectional magnetic field within the space defined by said inner cylindrical wall

45

and parallel to the axis thereof, and a cathode extending through said space parallel to the magnetic field; the end walls of the hollow body extending inwardly from said inner cylindrical wall to confine electrons emitted by said cathode to said space defined by said inner cylindrical wall.

14. A magnetron as recited in claim 13, in combination with insulating bushings supporting said cathode and mounted in relatively small openings in said extended end walls.

15. A magnetron as recited in claim 14, in combination with plates within the space defined by said inner cylindrical wall and immediately adjacent said extended end walls, said plates being insulated from said extended end walls and adapted to be maintained at a direct current potential of the order of the cathode potential.
